PAINTING MACHINE

Samuel Brand, Clayton, Mo.

Application November 24, 1937, Serial No. 176,163

7 Claims. (Cl. 91—50)

The present invention relates generally to coating or painting machines and to a cooperative method of coating or painting articles, and more particularly to a machine for and a method of 5 painting or coating the slats, headers, and the like, of Venetian blinds and similar constructions.

An object of the present invention is to provide a machine which is adapted to cooperatively coat or paint the sides and edges of a slat, 10 header, or the like.

Another object is to provide a machine which includes a novel unit for painting or coating the edges of slats, or similar pieces.

Another object is to provide a machine for 15 cooperatively painting or coating the sides and edges of slats, or similar pieces, which includes paint transferring rollers and painting or coating rollers, certain of which are individually adjustable to predetermine the amount of paint 20 being transferred and to space certain rollers for the reception of slats, or like pieces, of different thicknesses.

Another object is to provide a machine for 25 cooperatively painting or coating the sides and edges of slats, or similar pieces, which includes an edge painting or coating unit and a side painting or coating unit, each of which units includes a plurality of rotating elements which are driven by a common power means.

Another object is to provide a machine for 30 painting or coating slats, or the like, which includes a side painting or coating unit having an upper side painting section and a lower side painting section, the former of which is adapted 35 to be moved as a unit away from the latter for the reception of slats, or the like, of varying thickness.

Another object is to provide a machine for 40 painting or coating slats, or the like, which includes an edge painting or coating unit having rollers positively rotated about vertical axes and being of configurations to receive therebetween the slat, or similar piece, being coated, and revolving discs rotating about a common horizontal 45 axis for transferring paint from a container to the rollers.

Another object is to provide a machine which 50 is adapted to rapidly coat or paint the sides and edges of slats, or similar pieces, in an expeditious, efficient, speedy, and economical manner.

Other objects and advantages will be apparent from the following description, taken in conjunction with the accompanying drawings, in which:

Fig. 1 is a section taken on the line 1—1 of 55 Fig. 2, parts being broken away for clarity;

Fig. 2 is a view of one side of a painting or coating machine constructed in accordance with the concepts of the present invention;

Fig. 3 is a view of the other side of the machine shown in Fig. 2, certain parts being broken away 5 for the purpose of clarity and for conservation of space;

Fig. 4 is a section on the line 4—4 of Fig. 2; Fig. 5 is a section on the line 5—5 of Fig. 2; Fig. 6 is a section on the line 6—6 of Fig. 2; Fig. 7 is a section on the line 7—7 of Fig. 1; Fig. 8 is a section on the line 8—8 of Fig. 7; Fig. 9 is a section on the line 9—9 of Fig. 7; and,

Fig. 10 is an enlarged view of the edge painting 15 or coating unit, certain parts being broken away for the purpose of clarity.

Referring to the drawings more particularly by reference numerals, 15 indicates generally a painting or coating machine constructed in accordance with the teachings of the present invention. The various elements of the machine 15 are cooperatively assembled upon a supporting frame generally designated 16. The frame 16 is of skeleton construction and includes four 20 angle bar corner posts 17, 18, 19, and 20, one longitudinal top member 21, a second top member 22 downturned to include the downwardly extending portion 22' (Fig. 3), lateral top members 23, 24, and 25, lower longitudinal members 26 25 and 27, an intermediate longitudinal member 28, lower lateral members 29 and 30, and an intermediate lateral member 31. It is, of course, to be understood that the specific supporting frame can be varied according to the well-known principles of structural frame construction. The several elements of the supporting frame 16 are preferably maintained in assembled relation by bolts 16'.

The corner post 20 extends upwardly above 40 the frame 16 and supports a container 32 (Fig. 2) by means of a base 33 which is connected to the post 20 by a bolt 34 and a bracing strip 35. The container 32 includes in the bottom thereof an exit valve 36 by means of which fluid may be 45 drained from the container 32.

An edge painting or coating unit generally designated 38 (Figs. 6 and 10) is mounted on the frame 16 by means of the opposed upright members 39 and 40, the member 39 being bolted to the 50 longitudinal members 21 and 26 and the member 40 being bolted to the intermediate longitudinal member 28 and the lower longitudinal member 27.

The unit 38 includes a base generally design- 55

nated 41, the transverse cross-section of which is in the configuration of the Roman numeral II and includes upper and lower horizontal segments 42 and 43 and the connecting vertical segments 44 and 45. Two shafts 46 and 47 (Fig. 1) extend through aligned apertures in the sections 44 and 45 of the base 41 and are supported at their ends by the members 39 and 40. The member 39 has spaced apertures 48 and 49 (Fig. 2) which receive ends of the shafts 46 and 47, respectively, collars 50 determining the portions of the shafts 46 and 47 which extend into the apertures 48 and 49, respectively. The other ends of the shafts 46 and 47 rest in grooves 51 and 52, respectively, in the top edge of the member 40 (Fig. 3) collars 53 preventing longitudinal movement of the shafts 46 and 47.

A container generally designated 55 (Fig. 1) includes two side compartments 56 and 57 which are connected by the channel portion 58. The container 55 includes a connecting web 60 which is disposed against the top surface of the upper horizontal section 42 of the base 41 through which the container 55 is supported by the base 41.

Extending through respective sets of aligned apertures in the lower horizontal section 41, the upper horizontal section 42, and the web 60 are vertically disposed shafts 61 and 62 (Figs. 6 and 10). The shafts 61 and 62 are prevented from moving longitudinally downwardly by collars 63 and 64, respectively, which are fixed thereto and which rest upon the lower horizontal section 41. Rollers 65 and 66, preferably of hard rubber and of a configuration to substantially conform to the surface of the piece being painted or coated, are fixed by set screws, or the like, or by a snug fit, to the upper ends of the shafts 61 and 62, respectively. Bevelled pinions 67 and 68 are fixed by set screws, or the like, to the lower extremities of the shafts 61 and 62, respectively.

A horizontally disposed shaft 70 extends through aligned apertures in the vertical sections 44 and 45 of the base 41 for bearing support thereby, and projects at its free extremities into the interiors of the compartments 56 and 57 of the container 55. Discs 71 and 72 are mounted upon the free ends of the shaft 70 and are disposed within the compartments 56 and 57, respectively, (Figs. 1 and 6), the free extremities of the shaft 70 comprising reduced threaded extensions 73 and 74 which receive nuts 75 for maintaining the discs 71 and 72 in fixed relation relative to the shaft 70. Each of the discs 71 and 72 has a raised circular portion 76 of convex cross-section which cooperates with a concave portion of the rollers 65 and 66, respectively.

The shaft 70 is driven from the shaft 61 by a gear and pinion train which includes a gear 78 fixed to the shaft 70, a pinion 79 supported on a stub shaft 80 journaled in the vertical sections 44 and 45, an intermediate pinion 81 fixed to a stub shaft 82 likewise journaled in the vertical sections 44 and 45, and a beveled pinion 83 fixed to one end of the stub shaft 80 disposed in meshing relation with a beveled pinion 84 fixed to the shaft 61. The intermediate pinion 81 meshes with the gear 78 and the pinion 79.

A driven shaft 86 (Fig. 6) is disposed beneath the unit 38 and is journaled at its extremities in bearings 87 and 88 which are supported by angle brackets 89 and 90, respectively, which are bolted or otherwise fixed to the members 39 and 40, respectively. Beveled pinions 91 and 92 are fixed to the shaft 86 and mesh with the beveled pinions

67 and 68, respectively. A sprocket 93 is also fixed to the shaft 86.

A side, or top and bottom, painting or coating unit generally designated 100 is supported by and at one end of the frame 16, which comprises an upper section generally designated 101 and a lower section generally designated 102.

The upper section 101 includes a skeleton frame 103 of a rectangular box configuration (Figs. 1 and 2) which is slidably supported by a plate 104 which is bolted or otherwise secured to the upper transverse member 23 and the intermediate transverse member 31 of the supporting frame 16. The frame 103 comprises two upper longitudinal strips 105, two lower longitudinal strips 106, an upper lateral strip 107, a lower lateral strip 108 (Fig. 7), a laterally disposed end plate 109 opposed to the strips 107 and 108, two angle corner posts 110 at the ends of the lateral strips 107 and 108, and two angle bar posts 111 at the other end adjacent the plate 109. The plate 109 has a right angular extension 112 which includes a threaded enlargement 113.

An adjusting mechanism 116 for moving the frame 103 vertically is provided and includes a shaft 117 having a handle 118 fixed to one extremity by a lever 119. The shaft 117 extends through an aperture 120 in a right angular extension 121 of the plate 104 and is maintained in a selected position for rotation by collars 122 and 123 disposed at opposite faces of the extension 121. At its extremity remote from the handle 118 the shaft 117 is threaded and engages the threaded aperture of the enlarged portion 113. A nut 124 limits the upward movement of the frame 103.

A U-frame 126 (Fig. 7) is pivoted by legs 127 to the upper longitudinal strips 105 by nuts and bolts 128. A threaded shaft 129 engages a threaded aperture in the lateral strip 108 and includes a reduced extension 130 which is loosely connected to the bight 131 of the U-frame 126. At its end remote from the extension 130 the shaft 129 has a handle 132. Each of the legs 127 supports in fixed relation thereto a bearing 133. A shaft 134 is journaled in the bearings 133 and extends beyond the frame 103 on both sides (Fig. 1). A roller 135 is fixed to one extension of the shaft 134 and a gear 136 is fixed to the other extension of the shaft 134.

A second U-frame 138 (Figs. 7 and 9) is pivoted to the lower longitudinal strips 106 through its legs 139 by nuts and bolts 140. A threaded shaft 141 threadedly engages an aperture in the upper lateral strip 107 and includes a reduced extension 142 which loosely engages an aperture in the bight 143 of the U-frame 138. The shaft 141 has a handle 144 at the end remote from the reduced extension 142. Each of the legs 139 supports in fixed relation thereto two spaced bearings 145 and 146, the pair of bearings 145 being on one side of the U-frame 138 and the pair of bearings 146 being on the other side thereof. A shaft 147 is journaled in the bearings 145 and extends beyond the frame 103 on both sides thereof. A roller 148 is fixed to one extension of the shaft 147 and a gear 149 is fixed to the other extension thereof. A shaft 150 is journaled in the bearings 146 and extends outwardly beyond both sides of the frame 103. A roller 151 is fixed to one extension of the shaft 150 and a gear 152 is fixed to the other extension. It is thus apparent that the rollers 135, 148 and 151 are adjustably mounted.

A container 153 is supported by the frame 103.

beneath the rollers 135 and 148, the roller 135 dipping into the same.

The lower section 102 of the top and bottom coating unit 100 includes a frame 155 (Fig. 7) which is fixed to the supporting frame 16. The frame 155 includes upper longitudinal strips 156, lower longitudinal strips 157, an upper lateral strip 158, lower lateral strips 159, one pair of vertical corner strips 160, and a second pair of corner strips 161. The several members of the frame 155 are maintained as a sturdy unit by angle brackets 162 (Fig. 9). The frame 155 is fixed by any suitable means to the plate 104.

A U-frame 163 (Figs. 7 and 9) is pivoted through legs 164 of the vertical corner strips 160 by bolts 165. A bracket 166 is fixed to the bight 167 of the U-frame 163 and includes an apertured leg 168. A threaded shaft 169 having a handle 169' threadedly engages an aperture in one strip 159 and includes a reduced threaded extension 170 which extends through the aperture in and is loosely connected thereby to the leg 168. A bearing 171 is fixed to each leg 164. A shaft 172 is journaled in the bearings 171 and extends beyond both sides of the frame 155. A roller 173 is fixed to one extension of the shaft 172 (Fig. 3) and a gear 174 is fixed to the other extension thereof (Fig. 2).

A bearing 175 is fixed to each of the vertical strips 160 intermediate the ends thereof and receives journaled therein a shaft 176 which extends beyond both sides of the frame 155. A roller 177 is fixed to one extension of the shaft 176 and a gear 178 is fixed to the other extension thereof.

A second U-frame 180 (Figs. 7 and 9) is pivoted through legs 181 to the vertical strips 161 by bolts 182. A bracket 183 is fixed to the bight 184 of the U-frame 180 and includes a free leg 185 having an aperture therethrough. A threaded shaft 186 having a handle 186' threadedly engages an aperture in the other lower lateral strip 159 and includes a reduced threaded extension 187 which extends through the aperture in the leg 185 and is loosely connected thereby to the leg 185. Each of the legs 181 supports in fixed relation thereto a bearing 188 in which is journaled a shaft 189 which extends beyond the frame 155 on both sides thereof. A roller 190 is fixed to one extension of the shaft 189 and a gear 191 is fixed to the other extension thereof. It is thus apparent that the rollers 173 and 190 are individually adjustable, whereas the roller 177 is fixed to the frame 155.

A container 192 is disposed beneath the roller 190 and to one side of the frame 155 (Figs. 1 and 3). The container 192 is supported by the frame 16 through any suitable connecting and securing means.

A drive mechanism is provided whereby all of the foregoing enumerated movable parts are simultaneously driven by a single motor 195 which is supported by the frame 16 through the means of a plate 196 fixed to the lower lateral strip 23 and a transversely disposed supporting member 197.

The motor 195 includes a driven shaft 198 (Fig. 1) to which is fixed a drive pulley 199. A gear housing 200 is fixed to the plate 196 adjacent the motor 195. A pulley 201 is fixed to a shaft 202 journaled in the gear housing 200 and a sprocket 203 is fixed to a shaft 204 which is also journaled in the gear housing 200. The pulley 201 and the sprocket 203 are disposed at opposite sides of the gear housing 200. A continuous drive belt 194 operatively engages the pulleys 199 and 201.

An elongated vertical member 205 (Figs. 2 and 4) is connected to the upper longitudinal member 21 and the lower longitudinal member 26 by bolts 206 and 207, respectively. The member 205 extends above the frame 16 and terminates in a returned section 208 (Fig. 4) which is spaced from and connected to the member 205 by a connecting flange 209. The returned section 208 and the connecting flange 209 may be integral with the member 205 or connected thereto by bolts 210. Vertically spaced shafts 211 and 212 are journaled in aligned opposed apertures in the member 205 and the returned section 208 and are maintained in position by collars 213 and 214, respectively. A gear 215 and a sprocket 216 are fixed to the shaft 211, and a gear 217 and two sprockets 218 and 219 are fixed to the shaft 212. The gears 215 and 217 are in meshing relation. A continuous flexible chain 220 engages the sprocket 218 and the sprocket 203.

A second vertically disposed member 221 (Figs. 2 and 5) is fixed to the upper longitudinal member 21 and to the lower longitudinal member 26 by bolts 222 and 223, respectively. The member 221 is disposed between the member 205 and the member 40. The member 221 extends above the frame 16 and terminates in a right angular extension 224 (Fig. 5). A vertically disposed threaded shaft 225 threadedly engages an aperture in the extension 224. A stop nut 226 is disposed on the shaft 225 for selectively determining the extent of the downward movement of the shaft 225. An operating handle 227 is connected to the shaft 225 by a lever 228.

A U-frame 229 (Fig. 5) is mounted on the member 221 for vertical sliding movement, the U-frame 229 including spaced legs 230 and 231 and a bight 232. The leg 230 is disposed against one face of the member 221 and is maintained in sliding relation thereto by angle members 233 and 234, each of which engages the other face of the member 221 through one leg and the leg 230 through the other leg (Fig. 2). The shaft 225 extends through an aperture in the bight 232 and is maintained in engaging relation therewith by collars 235. A shaft 236 is journaled in aligned apertures in the legs 230 and 231, being maintained in predetermined relation therewith by a collar 237. The shaft 236 extends beyond the U-frame 229 and supports at the extremity 50 of the extension a roller 238 (Fig. 1). Laterally spaced sprockets 239 and 240 are fixed to the shaft 236 between the legs 230 and 231 of the U-frame 229. A continuous flexible chain 242 operatively engages the sprocket 240 and the sprocket 216. A continuous flexible chain 243 operatively engages the sprocket 239 and a sprocket 244 (Fig. 9) fixed to the shaft 150.

A second U-frame 245 (Fig. 5) is fixed to the member 221 beneath the U-frame 229 and includes legs 246 and 247 and a bight 248, the leg 246 being secured to the member 221 by bolts 249. A shaft 250 is journaled in aligned apertures in the legs 246 and 247, being maintained in predetermined relation therewith by collar 251. The shaft 250 extends beyond the U-frame 245 and has fixed to the extremity thereof a roller 238' which is disposed beneath the roller 238 for cooperation therewith. Sprockets 252 and 253 are fixed to the shaft 250 between the legs 246 and 247. A continuous flexible chain 254 operatively engages the sprocket 219 and the sprocket 253. A continuous flexible chain 255 operatively engages the sprocket 252 and a sprocket 256 fixed to the shaft 172.

A continuous flexible chain 257 operatively engages the sprocket 93 (Figs. 2 and 6) and a sprocket 258 fixed to the shaft 189 (Fig. 9). A stacking board 260 of relatively elongated configuration is fixed by bolts 261, or the like, to the transverse members 24 and 25.

The rollers, gears, pinions, and sprockets may be fixed to their respective shafts by set screws, splines, or the like. The rollers preferably are of hard rubber. The several members of the supporting frame and the auxiliary frames may be connected by bolts, welding, or the like, bolts being preferred in that such permits ready assembling and dismantling of the whole machine. 10 Idlers may be disposed at convenient points for taking up the slack in the chains which is sometimes incurred due to adjustment. It is apparent that all of these several variations and equivalents of construction are well within the 15 province of the invention and such is contemplated.

Operation

The operation of the machine which has been described in detail is positive and is effective in 25 painting or coating the edges and sides of slats, headers, and the like. The actual coating operations of the machine 15 are simple and efficient.

Slats are disposed upon the stacking board 260 in convenient feeding positions. Paint, 30 enamel, or the like, is disposed to sufficient depths in the containers 55, 153, and 192.

The rollers 135 and 148 are adjusted by the handles 132 and 144 to determine the amount of paint or enamel to be transferred from the 35 roller 135 to the roller 148. Similarly, the roller 190 is moved towards or away from the roller 177 by manipulation of the handle 186' to determine the amount of paint to be transferred from the roller 190 to the roller 177. The roller 173 40 is moved towards or away from the roller 177 by manipulation of the handle 169' to provide a finer adjustment of paint transfer, since the paint passes from the container 192 to the roller 190, to the roller 177, to the roller 173, and 45 thence to the bottom side of the slat, or the like, being coated.

The upper section 101 of the top and bottom painting unit 100 is adjusted by manipulation of the handle 118 towards or away from the lower 50 section 102 to space the roller 151 from the roller 173 in accordance with the thickness of the slats, or the like, to be coated. The U-frame 229 is similarly vertically adjusted through manipulation of the handle 227 to suitably space 55 the roller 238 and its associated roller.

Rollers 65 and 66 of suitable configuration are, of course, disposed on the vertical shafts 61 and 62, respectively. If preferred, coating material being used may be disposed in the container 32, 60 whence it may be passed by the valve 36 to the container 153.

The motor 195 is started through any convenient switch means which sets in motion all of the rollers, gears, sprockets, and other movable 65 parts, since they are all inter-connected for simultaneous movement by the several chains and the meshing gears and pinions.

A slat 262 is inserted between the roller 238 and its associated roller 238'. It is carried thereby between the rollers 65 and 66 where the edges thereof are coated, and thence between the rollers 151 and 173 where the top and bottom are coated. The operation is continuous, slats being fed between the roller 238 and its associated 70

roller 238' as fast as the preceding slat passes therefrom.

Paint is continuously supplied to the edge painting rollers 65 and 66 by the operatively disposed discs 71 and 72 (Fig. 10) which dip into the paint within the container 55. Paint is continuously supplied to the top coating roller 151 through the chain of rollers 135 and 148, the roller 135 dipping into the paint within the container 153 and passing it to the roller 148 10 which transfers it to the aforesaid top coating roller 151. Paint is continuously supplied to the bottom coating roller 173 by a chain of rollers, the lowermost disposed roller 190 dipping into paint within the container 192 and passing it upwardly to the roller 177 which, in turn, passes it to the aforesaid bottom coating roller 173. 15

It is thus apparent that there has been provided a painting or coating machine which effectively coats the edges and sides of slats, or similar pieces, in continuous succession. Both the edges and the sides of slats being treated are positively coated by the machine. Inasmuch as the paint, or the like, is passed from discs to rollers, or from rollers to rollers, which are disposed over the original containers, respectively, the splattering of paint and its attendant economic loss are substantially prevented. The several adjusting features of the machine make it possible to successfully coat the edges and sides of 25 relatively large pieces of material, since the roller which paints the tops of the pieces can be moved bodily a substantial distance away from the roller which paints the bottoms of the pieces. Further, the individual adjustments for the paint 30 transferring rollers assures the application to the coating rollers of the right amount of paint, which prevents waste and overcoating of the slats. The application of too much paint to slats is, of course, objectionable, not only from the 35 inevitable economic waste, but in that certain very heavily coated sections of the slat never properly dry.

It is to be understood that the foregoing description and accompanying drawings have been 40 given by way of illustration and example and not for purposes of limitation, the invention being limited only by the claims which follow.

What is claimed is:

1. In a device of the kind described, a support, 50 mechanism for coating the edges of elongated pieces of material including spaced coating rollers and associated paint supply discs, mechanism for coating the tops and bottoms of such pieces including a pair of spaced coating rollers and a plurality of paint supply rollers, and means for positively driving each roller and each disc.

2. In a device of the kind described, a support, and a unit for coating the edges of elongated pieces of material comprising a container, rollers rotatable about vertical axes adapted to coat the edges of such pieces, the surface of said rollers being depressed to form a groove of concave contour, discs rotatably mounted in said container adapted to transfer paint from the container to the rollers, each of said discs including an annular raised portion of convex contour, and means for simultaneously rotating said rollers and discs. 65

3. In a device of the kind described, a support, 70 a pair of vertically spaced superposed pivoted rollers, a container disposed beneath said rollers and spaced therefrom, means for transferring paint from said container to said lower roller including a pair of rollers one of which is pivotally mounted, a second container disposed 75

to one side of said upper roller, and means for transferring paint from said second container to said upper roller including a pair of pivotally mounted rollers.

5 4. In a device of the kind described, a support, a pair of individually pivotally mounted vertically spaced superposed rollers, a container disposed beneath said rollers and spaced therefrom, rollers at least one of which is pivotally mounted for transferring paint from said container to said lower roller, a second container disposed to one side of said upper roller, pivotally mounted rollers for transferring paint from said second container to said upper roller, and means for simultaneously adjusting the upper roller and its associated rollers to vary the vertical distance between the pair of rollers.

15 5. In a device of the kind described, a support, a pair of superposed frames mounted on the support, a pair of vertically spaced superposed rollers, one of said rollers being pivotally mounted on one frame and the other roller pivotally mounted on the other frame, a container disposed beneath said rollers and spaced therefrom, rollers for transferring paint from said container to said lower roller, a second container disposed to one side of said upper roller, rollers for transferring paint from said second container to said upper roller, and means for simultaneously positively rotating all of said rollers.

6. In a device of the kind described, a support, a pair of pivotally mounted vertically spaced superposed rollers, a container disposed beneath said rollers and spaced therefrom, rollers for transferring paint from said container to said lower roller, a second container disposed to one side of said upper roller, pivotally mounted rollers for transferring paint from said second container to said upper roller, means for adjusting certain of said rollers for varying the amount of paint supplied to the pair of rollers, means for adjusting certain rollers to vary the vertical distance between the pair of rollers, and means for simultaneously rotating all of said rollers.

10 7. In a device of the kind described, a support, and a unit for coating the edges of elongated pieces of material comprising a container, rollers rotatable about vertical axes adapted to coat the edges of such pieces, the coating surface of each roller being of a contour to substantially conform to the contour of the edge to be coated, and discs rotatably mounted in said container adapted to transfer coating material from the container to the rollers, each of said discs including an annular portion of a contour substantially complementary to the contour of the associated roller.

SAMUEL BRAND.
